To all whom it may concern:

Be it known that I, Rose Gottschalk, a citizen of the United States of America and a resident of New York, in the county and State of New York, have invented a new, original, and ornamental Design for Scarf, of which the following is a specification, reference being had to the accompanying drawing, forming a part thereof.

The figure is a plan view of a scarf showing my design.

I claim:

The ornamental design for a scarf, substantially as shown.
